SLICING MACHINE

John McLeod Little, Toledo, Ohio, assignor to
Toledo Scale Company, Toledo, Ohio, a corpora-
tion of New Jersey

Application January 26, 1951, Serial No. 13,985

Term of patent 14 years

(Cl. D55—1)

To all whom it may concern:

Be it known that I, John McLeod Little, a citizen
of the United States, residing at Toledo, in
the county of Lucas and State of Ohio, have in-
vented a new, original, and ornamental Design
for a Slicing Machine, of which the following is
a specification, reference being had to the accom-
panying drawings, forming a part thereof.

Figure I is a view in perspective of the rear of
a slicing machine embodying my new design.

Figure II is a view in perspective of the front
of the machine.

Figure III is a side elevation of that side of
the slicing machine shown to the left in Figure I.

Figure IV is a side elevation of that side of the
slicing machine shown to the left in Figure II,
being the side opposite that shown in Figure IV.

I claim:

The ornamental design for a slicing machine,
as shown.

JOHN MCLEOD LITTLE.
